INGOT STRIPPING APPARATUS

Emil Gathmann, Baltimore, Md.

Application June 28, 1932. Serial No. 619,807

54 Claims. (Cl. 22—95)

This invention relates to apparatus for stripping ingots from ingot molds, and more particularly to apparatus for this purpose including means for moving the molds of a "jag" successively to the stripping position, for holding the positioned molds against movement during the stripping operation, and for partially ejecting the contained ingots from the molds when the latter are held against movement.

10 It is well known that the best grades of steel produced at the present time are made from "big end up" ingots, i. e., ingots cast in molds the chambers of which are larger at the top than the bottom thereof. Molds of this type provide 15 for the extraction of heat from the molten ingot metal progressively from the bottom toward the top thereof so as to prevent the formation of pipes in the ingot body and to concentrate the shrinkage cavity and impurities at the extreme 20 upper portion of the ingot, so that a minimum amount of metal is lost through cropping.

Because of the greatly superior physical properties of steel cast in big end up molds as compared to that cast in big end down molds, the 25 use of the former kind of mold is increasing steadily, but even at present most steel is cast in big end down molds, due to the greater facility of handling such molds with the equipment now available in the mills.

30 The usual practice followed in stripping non-sinkhead ingots from big end up molds consists in inverting each mold individually after the ingot has solidified, lifting the mold off the ingot, and then lifting the ingot by means of 35 tongs or the like and removing it to the soaking pits.

This old practice of stripping big end up molds is somewhat more time consuming and consequently more expensive than the easier 40 process of stripping big end down molds, which consists merely in lifting the molds off the ingots without its being necessary first to invert the molds. This single factor operating in favor of the use of big end down molds is largely if not 45 entirely responsible for the continued use of such molds in spite of the fact that only inferior grades of steel can be produced therein.

In my copending United States applications Ser. No. 486,463, filed October 4, 1930, and Ser. 50 No. 567,281, filed October 6, 1931, I have shown, described and claimed stripping apparatus which are adapted particularly for stripping ingots from big end up molds. Apparatus embodying the present invention includes some features of 55 the constructions shown in the copending appli-

cations referred to, and further includes a novel general arrangement and novel details of construction which make possible a much more rapid stripping of ingots than is possible even with the apparatus disclosed in the copending applica- 60 tions referred to.

Generally stated, apparatus in accordance with the present invention includes a movable support for moving the molds of a jag successively to stripping position adjacent a stripping device, 65 a mold holding device mounted for movements into engagement with a mold in stripping position for holding the latter against movement during the stripping operation, and automatic control means interconnecting the means for operating the movable support, the stripping device, and the mold holding device so as to effect 70 operation of certain of the parts automatically to increase the speed with which a jag of molds may be stripped, and also to prevent accidental operation of the parts at the wrong time which otherwise might result in damage to the apparatus and in costly delays. Apparatus embodying the invention also includes independently of the interconnected control means, novel features of construction and arrangement of the mold positioning support, the mold holding device, and the stripping device.

An object of the invention is to provide an apparatus of the character described including 85 a movable mold support for positioning a mold in stripping position, a holding device mounted for movements into engagement with a positioned mold, a stripping device for effecting partial ejection of the contained ingot from a positioned 90 mold, and means controlling the operation of the mold support, the mold holding device, and the stripping device automatically or semi-automatically in accordance with a predetermined 95 sequence, and/or for preventing accidental operation of certain parts of the apparatus during certain periods of the operating cycle.

Other objects of the invention are to provide improved means for imparting step by step movements to the mold support for positioning successively the molds of a jag in stripping position; to provide an improved construction of mold holding device, and to provide improved means for operating the stripping device in a manner to cause the latter to exert a predetermined pressure 100 upon an ingot for stripping the latter, and automatically to exert a greater pressure upon the ingot to assure stripping of the ingot if the latter sticks to the mold to such an extent as to resist being stripped under the lower predetermined 105 110

- pressure. Other objects will become apparent from the following description, the appended claims, and the accompanying drawings.
- In the drawings:
- 5 Figure 1 is a side view, partly in elevation and partly in vertical section, of apparatus embodying the invention, and Figure 1^a is a similar view constituting a continuation or extension of Figure 1;
- 10 Figure 2 is a transverse vertical sectional view taken on the line 2—2 of Figure 1;
- Figure 3 is a transverse vertical sectional view taken on the line 3—3 of Figure 1, and drawn on an enlarged scale;
- 15 Figure 4 is a horizontal sectional view taken on the line 4—4 of Figure 3;
- Figure 5 is a transverse vertical sectional view of a rack and drive mechanism therefor taken on the line 5—5 of Figure 1, and drawn on an enlarged scale;
- 20 Figure 6 is a fragmentary top plan view of the drive mechanism shown in Figure 5, a gear case cover being removed;
- Figure 7 is a fragmentary plan view of certain switches and operating mechanism as viewed when looking in the direction of the arrow 7 in Figure 2 and drawn on an enlarged scale;
- 25 Figure 8 is a fragmentary plan view of switches and operating mechanism as viewed from the top of Figure 2 and drawn on an enlarged scale;
- Figure 9 is an enlarged detail view of switches arranged to be operated by a stripper plunger;
- 30 Figure 10 is a fragmentary vertical sectional view of a hold down screw and mold clamping head drawn on an enlarged scale; and Figure 10^a is a fragmentary horizontal sectional view taken on the line 10^a—10^a of Figure 10;
- Figure 11 is a view in front elevation of a valve 40 and valve operating means drawn on an enlarged scale;
- Figure 12 is a view in front elevation of a modified form of mold engaging head shown as engaging a mold of relatively large size;
- 45 Figure 13 is a view similar to Figure 12 but certain parts being shown in section and the head being shown in engagement with a relatively small mold;
- Figure 14 is a detail view in front elevation 50 of a mold engaging leg;
- Figure 15 is a sectional view taken on the line 15—15 of Figure 13;
- Figure 16 is a diagrammatic showing of an electrical control circuit for a rack operating 55 motor;
- Figure 17 is a diagrammatic showing of an electrical control circuit for a hold down screw operating motor;
- 60 Figure 18 is a diagrammatic showing of an electrical control circuit for a valve operating motor;
- Figure 19 is a diagrammatic showing of an electrical control circuit for another valve operating motor; and
- 65 Figure 20 is a sectional view taken on the line 20—20 of Figure 2.
- The embodiment of the invention shown by way of illustration in the accompanying drawings includes mold holding apparatus generally designated A for holding molds against movement during the stripping operation, ingot stripping apparatus generally designated B disposed in cooperative relationship with the holding apparatus A, and mold positioning means C for positioning successively the individual molds of
- 70 a jig of molds in stripping position relative to the mold holding and ingot stripping apparatus A and B. As shown in Figure 1, a plurality of molds D¹D²D³ is mounted in spaced relation upon a movable mold support in the present instance comprising a plurality of coupled cars E arranged to be moved relative to the mold holding and ingot stripping apparatus along tracks F. In Figure 1, D¹ represents molds the ingots contained in which have been partially stripped, D² represents a mold in stripping position, and D³—D³ represent molds which have not been positioned in the stripping apparatus and the contained ingots in which have not been stripped.
- 80 Referring to Figure 2, it will be noted that there are two rows of molds supported on each car E. Similarly, as will later be described, there are two holding devices for operating respectively on the molds of each row and two stripping devices for operating successively on the molds of each row. Inasmuch as the holding and stripping apparatus for operating in connection with one row of molds is the same as that for operating in connection with the other row of molds, the following description will refer specifically 85 only to the row of molds, the holding apparatus, and the stripping apparatus shown at the right of Figure 2, it being understood that the corresponding elements shown in the left of Figure 2 are exactly the same. Similar reference 90 characters are used to designate the corresponding elements of the apparatus shown on each side of the figure, with the exception that the reference characters applied to the elements on the left are primed.
- 95 Each of the cars E is formed with a plurality of spaced pads 1 which serve to assist in the locating of stools 2 each comprising a marginal part 3 and a horizontal web 4 spaced midway between the upper and lower faces of the marginal 100 part 3 to provide a bottom depression 5 and a top depression 6. As shown in Figures 1 and 2, the pads 1 are adapted to extend up into the bottom depressions 5 of the stools so as to assist in locating or centering the latter. The molds are formed 105 on their bottom faces with marginal seats 7 adapted to rest upon the top faces of the marginal parts 3 of the stools, and with centrally disposed pads 8 adapted to extend down into the top depressions 6 of the stools 3, the pads 8 cooperating 110 with the stools to assist in locating the molds in the desired spaced relation. The stools 2 and their mounting upon the cars E do not necessarily constitute any part of the present invention and it will be understood that in practicing the 115 invention the stools may, if desired, be omitted and the molds supported directly upon the cars.
- 120 The molds shown are of the big end up kind, that is, the ingot-forming chambers thereof are of greater cross section at the top than at the bottom, and consequently stripping of the ingot must be effected in a direction upwardly from the bottom to the top of the mold. The molds shown are provided with tapered bottom openings 9 which, when the molds are positioned on the 125 stools as described above, are aligned with openings 10 in the stool and with openings 11 in the car. Refractory or metallic closure plugs 12 are seated in the openings 9 of the molds prior to the teeming of the latter.
- 130 Stripper rods 13 are mounted for vertical reciprocation in the openings 11 in the car and are provided with heads 14 adapted, when the rods are in their lower positions, to be seated upon the pads 1 on the car so as to limit the downward 135
- 140 movement of the rods.
- 145 Stripper rods 13 are mounted for vertical reciprocation in the openings 11 in the car and are provided with heads 14 adapted, when the rods are in their lower positions, to be seated upon the pads 1 on the car so as to limit the downward 150 movement of the rods.

- movement of the stripper rods. The heads 14 are considerably smaller in diameter than the openings 10 in the stools and the openings 9 in the mold bottoms so as to permit the heads' being 5 raised through the openings 10 and 9 without danger of contacting with the sides of these openings, even though the molds are not centered absolutely accurately with respect to the stripper rods.
- 10 Each stripper rod is formed with a longitudinally extending slot or groove 15 which is provided with a pair of spaced notches 16. A straight latch rod 17 is mounted for sliding movements in guides 18—18 formed in the car, and is provided 15 at its outer end with a handle 19, the inner end of the rod having sliding engagement with the stripper rod 13 in the groove 15 thereof and being urged constantly to the bottom of the groove by means of a spring 20.
- 20 In operation, assuming the parts thus far described to be in the positions shown in Figures 1 and 2, and assuming the mold D² to be held down on top of the car E by means to be described later, stripping of the ingot in the mold D¹ is effected by 25 raising the stripper rod 13 in a manner later to be described so as to cause the head 14 of the rod to move upwardly through the openings 10 and 9 and to engage the closure 12 so as to move the ingot upwardly with respect to the mold. When 30 the rod 13 has been moved upwardly to such an extent as to bring the uppermost of the notches 16 opposite the latch rod 17, the latter will be forced into the notch under the urge of the spring 20, thereby maintaining the rod and ingot in their 35 raised positions, after which the mold is released by the holding means and may be moved away from the stripping and holding apparatus. Preferably air is allowed to circulate up through the openings 10 and 9 into the mold and thence up 40 through the space between the mold and the partially stripped ingot in order to effect solidification of the ingot in accordance with the method disclosed and claimed in my copending application Ser. No. 621,100, filed July 6, 1932. To this 45 end the car is provided with a plurality of openings 20^a under each stool 2, the arrangement being such that when the ingot is partially stripped air will flow up through the openings 20^a in the car, the opening 10 in the stool, the opening 9 in the 50 mold, and thence up through the mold. The nature of the solidification produced by the flow of air is described in detail in the copending application referred to.
- 55 As previously stated, it is necessary to hold the molds down upon the cars when the stripping operation is performed. For accomplishing this purpose, I provide the mold holding apparatus A previously referred to generally and shown as including a tower 21 consisting essentially of 60 braced vertical members 22 and horizontal top members 23 upon which is positioned a frame casting 24. The frame 24 is formed with two housings 25—25' spaced laterally the same distance as the center to center distance of the rows of molds. Captive nuts 26 and 26' are mounted in the housings 25 and 25' respectively, and each is arranged to operate means for engaging the top faces of the molds underneath for holding the latter against vertical movement during the 65 stripping operation. Referring more specifically to the nut 26 shown at the right of Figure 2 and to the associated mechanism, this nut is mounted for rotation in bearings 27 positioned in the housing 25 and is held against upward movement by 70 a thrust bearing 28. A worm gear 29 is fitted 75
- around and secured to the outside of the nut 26 and is in mesh with a worm 30 fixed to a shaft 31 which is arranged to be driven by an electric motor 32 through the medium of intervening reduction gearing 33. The motor is reversible and 80 may be controlled in a manner to be described later so as to drive the worm 30 to operate the nut 26 in either direction of rotation.
- 85 The nut 26 is formed with a vertical interiorly threaded bore which receives and cooperates with an exteriorly threaded rod or screw 34 which is guided for vertical movements in bearings 35 and 36 in the housing 25. The screw 34 is formed with a longitudinally extending slot or groove 37 which receives for sliding movements a key or spline 38 secured to the bearing 36, the key 38 thus cooperating with the slot in the screw to prevent rotation of the latter.
- 90 At its lower end portion, the screw 34 is formed with a reduced part or neck 39, and, at its extreme lower end, is provided with an enlargement 40 disposed in a recess 41 of a clamping head 42 mounted on the screw for limited vertical movements relative thereto. Split plate halves 43—43 conjointly formed with a centrally disposed inwardly directed overhanging part or flange 44 defining an opening 45 through which the neck 39 of the screw passes are secured to the clamping head 42 and prevent the withdrawal of the enlargement 40 of the screw from 100 the recess 41 in the head. As shown in Figure 10, the distance between the bottom of the recess 41 in the head 42 and the flange 44 is somewhat greater than the depth of the enlargement 40 on the screw so as to provide sufficient clearance 105 to permit limited vertical movement of the head 42 relative to the screw, the arrangement, in effect, constituting a lost motion connection between the head and the screw. The projecting ends 46 of pins secured to the enlargement 40 110 on the end of the screw are disposed in slots 47 formed in opposite sides of the recess 41 in the head 42 in order to hold the head against rotary movement relative to the screw. The head 42 is provided with a pair of spaced downwardly 115 extending legs 48 adapted to engage the opposite sides of the top face of a mold positioned under the screw when the latter is moved downwardly. Normally, the head 42 will be in a position out of contact with the mold underneath. 120 In this position of the screw and head, they will be in the relative positions to each other shown in Figure 10, from which it will be noted that, the head 42 being suspended from the lower end of the screw 34, the flange 44 on the head will be 125 in engagement with the enlargement 40, and there will be considerable clearance between the bottom end of the screw and the bottom of the recess 41 in the head. When it is desired to move the head into engagement with the mold 130 so as to hold the latter in stripping position, the motor 32 is run in a direction to drive the screw 34 downwardly. When the legs 48 of the head 42 engage the top face of the mold, the head will become supported by the mold, and further 135 downward movement of the head will be prevented. However, the screw will continue to move downwardly until the extreme bottom end thereof engages the bottom of the recess 41 in the head, whereupon the motor 32 will be stopped 140 automatically in a manner later to be described.
- 145 The mechanism for controlling the operation of the motor consists partly in means carried by the screw 34 and responsive to engagement of the head 42 with a mold for breaking a circuit 150.

through the motor. The screw 34 is formed with a central bore 49 in which a rod 50 is mounted for sliding movements, the lower end of the rod resting against the bottom of the depression 5 41 in the head 42 and the upper end of the rod extending through a guide 51 secured to the top end of the screw. An angle member 52 is secured to the top end of the rod 50 and is adapted, when the latter is raised relative to the screw, 10 to engage and operate simultaneously three limit switches I, II, and III carried by a bracket 53 fixed to the upper end of the screw 34. When the screw and head are in the relative positions shown in Figure 10, the rod 50 will occupy a 15 lower position with its bottom end in contact with the head 42 and with the angle member 52 disposed below the operating arms of the limit switches I, II, and III. When the screw is moved downwardly and the head into engagement with 20 the mold so as to produce movement of the screw downwardly relative to the screw in the manner heretofore described, the rod 50 will be moved upwardly relative to the screw and to the switches I, II, and III, resulting in engagement 25 of the angle member 52 with the switches and operation of the latter. As will be described later, operation of the switch I automatically will stop the motor 32, whereupon the screw and head will be maintained in the positions shown in 30 Figures 1 and 2 until the motor has been reversed and the screw and head retracted. The other limit switches II and III are operated simultaneously with the limit switch I by the angle member 52, operation of the switches effecting automatic control of the means for positioning the molds under the screw and the means for operating the stripper rod respectively in a manner fully to be described later.

In order to provide for automatically stopping the motor 32 when the head 42 has been raised clear of a mold underneath, I provide a limit switch IV mounted on a vertical member 22 of the tower and disposed in the path of an arm 55 carried by the head 42. In operation, when the screw and head are moving upwardly, the arm 55 will engage the operating arm of the switch IV and will open the latter so as to stop the motor and bring the screw and head to rest. The switch IV is positioned at such a height that it will be operated to stop the motor when the screw has been raised to a position providing a safe clearance between the bottom of the head and the top of the molds. In some cases it is necessary that the locomotive which brings the cars from the pouring station to the stripping apparatus pass under the tower 21. In such cases it may be necessary to raise the screw and head to a position considerably higher than that in which they are stopped by the operation of the switch IV. Accordingly, I provide means to be described later for effecting continued operation of the motor after the switch IV has been operated. In order to prevent overtravel of the screw and head during their upward movement, I provide another switch V mounted on a cross member 23 of the tower and having its operating arm disposed in the path of the arm 55 on the head. When the screw and head have been moved upwardly to an extent providing the 50 clearance which may be necessary for the passage of the locomotive, the arm 55 will engage the operating arm of the switch V and will actuate the latter in a manner to stop the motor 32, thereby preventing overtravel of the screw and head and insuring against damage to the 75

parts. In order to prevent overtravel of the screw downwardly, for example, when no mold is positioned under the screw and the latter is moved downwardly through inadvertence, I provide a limit switch VI mounted on the frame 24 and having its operating arm disposed in the path of the bracket 53 on the screw. When the screw moves downwardly toward the limit of its travel, the bracket 53 will engage the operating arm of the switch and actuate the latter to stop the motor, the breaking of the circuit through the motor being accomplished under the control of the switch VI by means to be described later.

Referring now to the mechanism B for operating the stripper rods 13-13', two hydraulic cylinders 56-56' are mounted directly under the screws 34-34' respectively, being carried by brackets 57-57' depending from a floor plate 58. The mechanism associated with the cylinder 56 only will be described, it being understood that that associated with the cylinder 56' is similar and that the parts thereof are designated by corresponding reference numerals, which, however, are primed. A stripper plunger 59 is mounted in the cylinder 56 and is provided with a reduced stem 60 mounted for sliding movements in a guide bearing sleeve 61 carried in a projection 62 formed on the floor plate 58. An apron 63 is secured to the stem 60 of the plunger, and an angle section 64 is connected to the apron and extends outwardly therefrom for co-operation with the operating arms of switches VII, VII' and VIII mounted on the tower structure base as shown in Figures 2, 9 and 20. The operating arm of the switch VIII is urged upwardly but is adapted to be held in its Figure 2 position by the extension 64 when the plunger 59 is in its lower position, this switch serving to control operation of the means for positioning molds under the plungers, as will be described more fully later. The operating arms of the switches VII and VII' are adapted to be engaged by the projection 64 when the plunger 59 is raised in order respectively to effect control of the operation of the plunger so as to bring the latter to rest after the stripping operation has been performed and automatically to effect operation of the screw motor 32 in the reverse direction to start the screw moving upwardly.

In accordance with one feature of the invention, I provide means for supplying fluid under relatively low pressure and at a high rate to the cylinder 56 for raising the plunger 59 into engagement with the stripper rod 13 and for raising the latter to strip the mold when there is no unusual sticking of the ingot in the mold, and means for supplying fluid under relatively high pressure and at a relatively low rate for raising the plunger 59 upwardly when the ingot sticks in the mold to such an extent as to offer sufficient resistance to the operation of the plunger to resist the pressure supplied by the low pressure, high rate supply means. In the form shown, I provide a pump 65 adapted to deliver fluid under relatively low pressure but at a relatively high rate, a pump 66 adapted to deliver fluid under relatively high pressure but at a relatively low rate, a motor 67 connected to both of the pumps for driving the latter, and hydraulic connections between the pumps and the cylinders 56 and 56'. The motor 67 is arranged to drive the pumps continuously, the supply of fluid under pressure to the cylinders being controlled by means of 130 135 140 145 150

valves interposed in the connected piping. Both pumps are preferably of the well known radial variable discharge type, for example, such as is shown in Patent No. 1,077,979, granted to Hele-
 5 Shaw et al. November 11, 1913. The construction and operation of pumps of this kind are well known, and no detailed description thereof is considered necessary. The pumps 65 and 66 are provided respectively with control mechanism 68
 10 and 69 for limiting the maximum discharge pressure of each, the control mechanism also being of well known construction, so that no disclosure of the details thereof is necessary. Generally stated, the arrangement is such that when the
 15 discharge pressure reaches a predetermined value the control mechanism will operate to decrease the rate of discharge of the pump to maintain the discharge pressure at a predetermined maximum value. The control mechanism 68 of
 20 the pump 65 is arranged to limit the discharge pressure of the latter to a thousand pounds per square inch, and the control mechanism 69 of the pump 66 is arranged to limit the maximum discharge pressure thereof to three thousand
 25 pounds per square inch.

A pipe line 70 leads from the pump 65 to the cylinder 56, and a branch pipe 71 leads from the pump 66 to the pipe line 70. Suction pipes 72 and 73 are connected between the pumps 65
 30 and 66 respectively and a tank or reservoir T. A three way valve 74 of conventional design is interposed in the pipe line 70, and a branch pipe line 70' leads from the valve 74 to the cylinder 56'.

The valve 74 is provided with a stem 75 (see Figure 11) the position of which controls the passage of fluid through the pipe lines 70 and 70'. When the stem is in its lower position relative to the valve casing, fluid will flow through the pipe line 70, to the cylinder 56, but when the stem is moved to its upper position the valve will divert fluid from the pipe line 70 and direct it through the pipe line 70' to the cylinder 56'. Thus, by changing the position of the stem 75, the fluid supplied by the pumps 65 and 66 may be directed either to the cylinder 56 or to the cylinder 56' in order to operate either the plunger 59 or the plunger 59', whichever may be desired. A cross bar 76 is secured to the casing of the valve 74, and two spaced guide rods 77 are secured to the cross bars and are connected at their lower ends by means of a bar 78. A cross head 79 is secured to the stem 75 and is mounted for sliding movements on the guide rods 77. Springs 80 interposed between the cross bar 76 and the cross head 79 urge the latter constantly to its lower position, wherein fluid will be directed through the pipe 70 to the cylinder 56. Thrust rods 81 connected to the cross head 79 extend downwardly for connection with a motor actuated mechanism 82. Operation of the mechanism 82 under the control of means later to be described will effect an upward movement of the thrust rods 81, and consequent movement of the valve stem 75 to its upper position wherein fluid will be diverted from the cylinder 56 and will be delivered to the cylinder 56'. As is apparent from the foregoing description, the three way valve 74 functions to cause fluid discharged by the pumps 65 and 66 to be directed either to the cylinder 56 or the cylinder 56', as is desired.

When it is desired to maintain the plungers 59 and 59' in their retracted positions, and also when it is desired that the plungers be allowed to re-

turn to their retracted positions after completion of the stripping operation, it is necessary to divert the flow of fluid from both cylinders. For effecting the diverting of fluid or the exhausting of fluid from the cylinder 56, I provide a fluid exhaust pipe 83 connected at one of its ends to the pipe 70 between the valve 74 and the cylinder 56 and connected at its other end with the tank T, and a two way valve 84 of conventional design interposed in the exhaust pipe 83. The valve 84 is provided with a stem 85 which is movable vertically to an upper position to prevent the flow of fluid through the exhaust pipe 83 and to a lower position to permit the free flow of fluid through the pipe 83, it being noted that when the stem is in the upper position, preventing flow of fluid through the pipe 83, fluid discharged through the pipe 70 cannot return to the tank and will be directed to the cylinder 56. A cross bar 86 is secured to the casing of the valve 84, and guide rods 87 carried by the cross bar extend downwardly therefrom and are connected at their lower ends by a bar 88. A cross head 89 is connected to the valve stem 85 and is mounted for sliding movements on the rods 87. Springs 90 interposed between the cross bar 86 and the cross head 89 urge the cross head and the valve stem 85 constantly to their lower positions, wherein fluid is permitted to pass through the exhaust pipe 83. Thrust rods 91 connected to the cross head 89 extend downwardly for connection with a motor operated mechanism 92 which is operated under the control of means to be described later for raising the thrust rods 91 and the stem 85 so as to cut off flow through the valve 84 and consequently through the pipe 83.

A two way valve 84' similar to the valve 84 and provided with control mechanism similar to that described in connection with the valve 84 is interposed in an exhaust pipe 83' one end of which is connected to the piping 70' and the other end of which is connected to the tank T. When the stem 85' of the valve 84' is in its lower position, the pipe 70' will be afforded free communication with the tank T, whereas, when the mechanism 92' is operated to raise the stem 85', flow of fluid through the pipe 83' will be prevented.

In operation, assuming that the parts are in the position shown in Figure 2, the stem 75 of the valve 74 will be held in its lower position under the urge of the springs 80, so that the discharge from the pumps will be directed towards the cylinder 56, and the stem 85 of the valve 84 will be held in its lower position under the urge of the springs 90 so as to permit the free flow of fluid through the exhaust pipe 83. Fluid discharged through the pipe 70 thereby will be by-passed through the pipe 83 to the tank T, so that no pressure will be exerted upon the plunger 59. When it is desired to raise the plunger 59 into engagement with the stripper rod 13 so as to effect stripping of the ingot, the motor mechanism 92 associated with the valve 84 is operated to move the stem 85 to its upper position so as to cut off flow through the pipe 83. Thereafter fluid discharged through the pipe 70 will be directed to the cylinder 56 and will act upon the plunger 59 to raise the latter to strip the ingot. It will be understood that both pumps 65 and 66 supply fluid under pressure to the pipe 70 and to the cylinder 56 to effect operation of the plunger 59. Should the ingot stick to the mold so as to present an abnormal resistance to the movement of the plunger 59, pressure will build up in the cylinder 56 to a valve beyond the maximum dis-

150

charge pressure of the pump 65 but less than the maximum discharge pressure of the pump 66. When this occurs, a check valve 93 interposed in the pipe 70 between the pump 65 and the pump 66 and arranged to permit flow of fluid in the direction of the arrow X in Figure 2 but not in the opposite direction will be closed by the excess pressure on the left hand side of the valve. This will prevent the fluid discharged from the pump 66 from being forced back through the pump 65, so that the total discharge of the high pressure pump 66 will be delivered to the cylinder 56 so as to overcome the pressure offered by the sticking of the ingot. While the check valve 93 is held closed so as to prevent back discharge of fluid into the pump 65, the control mechanism 68 will operate in a well known manner to prevent further discharge of the pump. When the plunger 59 has been raised to the extent necessary to strip the ingot and to bring the uppermost notch 16 of the stripper rod opposite the end of the latch rod 17, the projection 64 on the apron 63 will operate the switch VII so as to break a circuit through the motor operated mechanism 92 and to permit the springs 90 to return the stem 85 of the valve 84 to its lower position wherein flow of fluid is permitted through the valve and through the exhaust pipe 83. Fluid contained in the cylinder 56 will then be expelled through the pipe 70 and the exhaust pipe 83 to the tank T, and the plunger 59 will descend to its retracted position. In order to effect operation of the plunger 59', the motor operated mechanism 82 is energized to move the valve stem 75 to its upper position so as to direct the discharge from the pumps through the pipe 70' to the cylinder 56'. The valve 84' will then be closed in the manner already described to prevent flow of fluid through the exhaust pipe 83', and fluid will be directed through the pipe 70' to the cylinder 56' to move the plunger 59' upwardly. The valve 84' will then be opened to permit fluid contained in the cylinder 56' to return through the pipe 70' and the exhaust pipe 83' to the tank T so as to permit the plunger 59' to descend to its lower position.

Referring now to the mold positioning means C best shown in Figures 1, 3, 4, 5, and 6, a rack bar 94 disposed longitudinally of the tracks F and midway between the latter is provided at its opposite ends with transverse shafts 95 upon the projecting ends of which are journalled wheels 96 having rolling engagement with the bottom flanges of longitudinally disposed I beams 97. The right hand end of the rack bar, as viewed in Figures 1 and 4, is bifurcated to provide a pair of spaced arms 98. A pin 99 fixed in these arms and extending across the intervening space serves to mount pivotally a pawl 100, the nose 101 of which is adapted, when the pawl is rocked in a counter clockwise direction as viewed in Figure 1, to be received in an opening 102 formed in a downwardly extending part 103 of one of the cars E or between two adjacent cars. The pawl 100 extends up through a slot in the floor plate 58 (see Figure 2) and is movable longitudinally of the tracks F with the rack 94. Both ends of each car E are provided with downwardly extending sections 103 formed with openings 102, each of which openings is adapted to receive the nose 101 of the pawl when the latter is moved upwardly from below an opening 102.

The pawl is formed with a weight arm 105 disposed on the opposite side of the pin 99 from the nose 101, this weight serving constantly to urge the nose of the pawl upwardly into operative

position. In order to provide for the actuation of the pawl to disengage the nose 101 thereof from a car, I provide means engageable with the pawl irrespective of the position of the rack bar for rotating the pawl in a clockwise direction to move the nose 101 downwardly. In the embodiment shown in the drawings, this means includes a pair of spaced levers 106—107 located under the rack bar, these levers being similar and of equal length. The lever 106 is carried by a pin 108 supported in a fixed bracket 109, and the lever 107 is secured to a rock shaft 110 journalled in a fixed bracket 111. A rail 112 (see Figure 1) is pivoted at its opposite ends to the levers 106 and 107, the levers and the rail 112 constituting a parallelogram linkage. A hand lever 113 (see Figure 3) is fixed to the shaft 110 and is operable to rock the latter and the levers to the left to move the rail 112 downwardly or to rock the levers to the right to move the rail upwardly with respect to the rack, maintaining the rail parallel to the rack at all times. When the rail is moved upwardly, it will engage a roller 114 carried by a pin 115 supported at the lower side of the weight arm 105 of the pawl. In operation, assuming the parts to be in the Figure 1 position, in order to effect disengagement of the nose 101 of the pawl from the car, the hand lever 113 will be operated to rock the levers 106 and 107 toward the right as viewed in Figure 1. This will raise the rail 112 into engagement with the roller 114 so as to rock the pawl in a clockwise direction, thereby moving the nose downwardly and out of engagement with the car. The rack then may be moved to the left without the car's being moved, and the rail 112 lowered so as to permit the nose 101 of the pawl again to move upwardly and to engage an opening 102 in a car near the left hand end of the travel of the rack. It will be observed that the rail 112 is engageable with the pawl roller 114 irrespective of the position of the rack longitudinally of the tracks F.

It is desirable to provide means engageable with the pawl 100 when the latter is in operative position as shown in Figure 1 for preventing accidental disengagement of the pawl. To this end a latch 116 is mounted on a pin 117 carried by the arms 98 at the right hand end of the rack. The nose 118 of the latch is engageable with the top face of a projection 119 on the weight arm 105 of the pawl when the latter is in operative position. With the latch in the position shown in Figure 1, it will not be possible for the pawl to become disengaged from the car. The bottom arm 120 of the latch is disposed at an angle to the arm carrying the latch nose, and the weight of the arm 120 urges the latch in a clockwise direction so as to drop into engagement with the projection 119 of the pawl when the curved lower face of the projection 119 passes the curved upper face of the nose 118 on the latch. Thus, assuming the pawl to be in its inoperative position with the projection 119 located above the latch nose 118, and assuming the rail 112 to be lowered so as to permit the weight arm 105 of the pawl to be lowered, the projection 119 momentarily will move the latch nose to the left, after which the latter will drop into the position shown in Figure 1 and will maintain the pawl against accidental displacement. A roller 121 mounted on a pin 122 carried by the lower arm of the latch is engageable by the rail 112 when the latter is raised so as to cause the latch to be rocked in a counter clockwise direction to swing the nose 118 thereof

clear of the projection 119, permitting the pawl to move to its inoperative position.

Means for operating the rack in both directions are illustrated in Figures 5 and 6. A motor 123 is geared through a speed reducing gear train 124 to a shaft 125 supported in fixed bearings 126. A pinion 127 fixed to the shaft is in mesh with the rack 94. The motor is provided with a conventional automatic brake 128 which functions to stop the motor quickly when a mold has been "spotted" in stripping position. The operation of the motor for driving the rack is controlled in part by manually operated means and in part by means automatically responsive to the movement of certain parts of the apparatus, as will be set forth more fully.

Referring to Figures 2 and 7, each car E is provided with a plurality of spaced projections 131 each of which is aligned with a pair of openings 11 in the associated car, and hence with the associated stripper rod 13. Vertically spaced switches IX and X are mounted on a vertical member 22 of the tower structure substantially in a vertical plane containing the screws and stripper plungers. The switch X is not shown in Figure 7 because it is located directly under the switch IX. A bracket 132 likewise carried by the vertical members 22 of the tower serves to mount pivotally a pin 133 disposed in the plane containing the screws and stripper plungers, and a lever 134 is carried by the pin 133. One arm 135 of the lever is disposed for engagement by an advancing projection 131 on a car, and the other arm 136 of the lever is adapted to engage the operating arms of the switches IX and X when the lever 134 is rocked by the advancing projection 131. A spring 137 connected between the arm 135 of the lever and a fixed bracket 138 normally maintains the lever out of engagement with the operating arms of the switches.

In operation, assuming that the rack motor is started so as to advance the rack and the mold cars to position the next mold under the screws, the rack and cars will move to the right as viewed in Figure 1 until the projection 131 opposite the mold moving into position engages the lever 134 so as to rock the latter and operate the arms of the switches IX and X. As will be described later, the operation of the switch IX at this time will stop the rack motor automatically, thereby bringing the cars to rest with the ingot mold positioned directly under the screw, and the operation of the switch X will prepare the screw motor circuit for being closed by the manual operation of another switch. Limit switches XI and XII mounted at opposite ends of the rack supporting rails 97 are adapted to be operated by the rack at limits of its forward and reverse travel respectively for preventing overtravel of the rack.

Figures 12 to 15, inclusive, show a modified form of mold engaging head adapted to be carried by the lower ends of the screws 34, the heads embodying the invention in this form being adjustable to adapt the downwardly extending legs for engagement with opposite sides of the top faces of molds of different sizes. The modified form of head generally designated 139 comprises a body part 140 formed along its outer edges with spaced depending flanges 141 formed along their inner faces with slots or grooves 142. A pad 143 is disposed between the flanges 141 at the center of the body 140. Two mold engaging legs 144 are mounted at their top ends between the flanges 141 of the body for sliding movements relative to the body, the legs being provided on their opposite

sides with tongues 145 which fit in the grooves 142 of the body flanges. The upper ends of the legs 144 are formed with reversely threaded openings 146 which respectively receive the reversely threaded ends of a captive screw 147. Collars 148 fixed to the screw at the inner ends of the threaded portions thereof engage the pad 143 for holding the screw against longitudinal movement. Hand wheels 149 fixed to the opposite ends of the screw 147 provide for the rotation of the latter to cause the legs 144 to move inwardly or outwardly in order to adapt the head for cooperation with molds of relatively small or relatively great width.

The control circuit for the rack operating motor 123 is shown diagrammatically in Figure 16. The motor is arranged to be supplied with power from a supply main comprising conductors 150 and 151. The shunt field of the motor is connected directly across the main by means of a conductor 152, a cut-out switch 153 being interposed in the conductor to permit the motor circuit's being totally disconnected from the line when desired. The opposite sides of the motor armature are connected to mid points of conductors 154 and 155, the opposite ends of these conductors being connected respectively by conductors 156 and 157. The conductor 156 is connected to the side 151 of the main line, and the conductor 157 is connected to the side 150 of the main, a series field and series brake being interposed in series between the conductor 157 and the side 150 of the main.

Contactor switches 158 and 159 are interposed in the conductor 154 on opposite sides of its point of connection to the armature, and contactor 110 switches 160 and 161 are interposed in the conductor 155 on opposite sides of its connection to the armature. The switches 159 and 161 are of the well known double contact type, and are so arranged that when in their lower positions, as shown in Figure 16, they will close a circuit through a brake resistance 162, connecting the latter directly across the armature to effect regenerative braking of the rack motor.

The arrangement is such that, when the coils 120 of the contactor switches 159 and 160 are energized, these switches, being closed, will complete a circuit through the motor armature in such a direction as to cause the motor to operate the rack in a forward direction, whereas, when the coils 125 of the switches 158 and 161 are energized to close these switches, the circuit will be closed through the armature in the opposite direction to reverse the motor and to operate the rack in the reverse direction.

The contactor switches previously referred to are arranged to be operated automatically in accordance with the movements of the mold cars, the hold-down screw, and the stripper plunger. A conductor 163 leads from the side 151 of the main through the normally closed limit switch II carried by the hold-down screw 34, the normally closed limit switch II' carried by the screw 34', the limit switch VIII normally held closed by the plunger 59, and the limit switch VIII' normally held closed by the plunger 59'. A conductor 164 leads from the conductor 163 through a manually operated master switch 165, the normally closed car operated limit switch IX, the the normally closed rack operated limit switch XI, the coil of the contactor switch 160, the coil of the contactor switch 159, and thence to the side 150 of the main line. The limit switch IX is shunted by a manually operable push button 166.

130

135

140

145

150

A conductor 167 leads from the conductor 163 through a reverse master switch 168, the normally closed rack operated limit switch XII, the coil of the contactor switch 158, the coil of the contactor switch 161, and thence to the side 150 of the main.

In operation, assuming that the leading mold car has not been moved into position under the lower, the switches all will be in the positions shown in Figure 16 and the rack motor will be at rest. When it is desired to move the cars forwardly to position the first mold on the leading car directly under the hold-down screw, the master switch 165 is closed manually. This will 10 complete a circuit through the conductor 163, the switches II, II', VIII, VIII', 165, IX, and XI, the conductor 164, the contactor coil 160, and the contactor coil 159, closing the contactors 160 and 159 and causing the motor to drive the rack forwardly. When the first mold on the leading car arrives directly under the screw 34, the projection 131 opposite this mold will engage the operating arm 135 and will rock the lever 134 to 15 open the limit switch IX, thus breaking the circuit through the coils of the switches 159 and 160 and permitting these contactors to drop out, thereby stopping the rack motor. When either the head 34 or 34' has been moved into engagement with the mold, the rod 50, or 50' as the case 20 may be will be operated to open the switch II or II' in the manner previously described, thus preventing inadvertent operation of the rack motor when the mold is held by the head. Similarly if either the plunger 59 or the plunger 59' is 25 above its lower position, one or the other of the switches VIII or VIII' will be opened and inadvertent operation of the rack motor during a stripping operation will be prevented.

When the ingot has been stripped from the 30 first mold and it is desired to position the next mold under the screw 134, the push button 166 is closed momentarily to shunt the then open switch IX. The circuit will thereby be closed through the coils of the contactors 160 and 159, causing the motor to drive the rack and cars 35 forwardly. After the projection 131 has cleared the operating arm 135, the latter will be returned to its normal position by the spring 137, permitting the limit switch IX to close. The push button 166 is then opened, and the circuit through 40 the contactor coils 160 and 159 will be closed through the switch IX. When the next projection 131 engages the operating arm 135, the switch IX again will be opened to bring the next mold to rest in a position directly under the screw 134. In this manner the molds on the 45 several cars may be advanced successively to stripping position simply by closing the push button 166 momentarily after each mold is stripped. Should the rack reach the limit of its forward travel, it will open the limit switch XI so as to 50 prevent a circuit being closed through the coils of the contactor switches 159 and 160.

When it is desired to return the rack to its 55 rearmost position, the master switch 165 is opened, and the master switch 168 is closed. This will complete a circuit through the conductors 163 and 167, the master switch 168, the rack operated limit switch XII, the coil of 60 the contactor switch 158, and the coil of the contactor switch 161, whereby the switches 158 and 161 will be closed and the motor will operate in the reverse direction to return the rack to its rearmost position. In order to stop the 65 motor when the rack has reached the desired posi-

tion, the master switch 168 is opened. If the operator fails to open the master switch 168 before the rack reaches the limit of its rearward travel, the rack will engage and operate the limit switch XII to open position so as to break the circuit through the coils of the contactor switches 158 and 161 so as to bring the rack to rest automatically.

Figure 17 shows the electrical control circuit for the screw operating motor 32. The shunt field is connected directly across the line 150—151 by means of a conductor 169, a cut-out switch 170 being interposed in this conductor to enable the motor to be disconnected from the line when the apparatus is not in use.

Opposite sides of the armature of the motor 32 are connected to the mid points of conductors 170 and 171. The opposite ends of these latter conductors are connected by conductors 172 and 173, the conductor 172 being connected to the side 151 of the supply line and the conductor 173 being connected to the side 150 of the line. The series field of the motor and a contactor switch 174 are interposed in series between the conductor 173 and the side 150 of the supply line. 100 Contactor switches 175 and 176 are interposed in the conductor 170 on opposite sides of its connection to the motor armature, and contactor switches 177 and 178 are interposed in the conductor 171 on opposite sides of its connection to the armature. The contactor switches 176 and 178 are of the type well known as double contact switches and are adapted when both are in their Figure 17 positions to connect a brake resistance 105 179 directly across the motor armature so as to 110 effect regenerative braking of the motor 32.

The arrangement of the contactor switches referred to is such that, when the switches 175 and 178 are closed, the motor 32 will run in a direction to move the screw 34 downwardly, and, 115 when the switches 176 and 177 are closed, the motor 32 will run in the reverse direction to move the screw upwardly. The contactor switch 174 is normally open and is closed only when either pair 175—178 or 176—177 of contactor switches 120 is closed, the purpose of the switch 174 being to break the circuit through the shunt brake when the motor is not running.

The opening and closing of the contactor switches for effecting operation of the motor in 125 either direction is controlled automatically through the operation of limit switches previously referred to. In the control circuit shown, a conductor 179' leads from the conductor 172 through the car operated switch X and through 130 a contactor switch 180 which is normally closed and which is opened when fluid is being delivered to the cylinder 56, the operation of the switch 180 being described more in detail hereinafter. A push button 181 is connected across 135 the car operated switch X for closing the circuit when the switch X is held open.

A conductor 182 leads from the conductor 179' through a manually operable master switch 183, the limit switch I carried by the hold-down screw, 140 the limit switch VI mounted on the tower, the coil of the contactor switch 175, the coil of the contactor switch 178, the coil of the contactor switch 174, and thence to the side 150 of the main line. In operation, assuming that no mold 145 has been positioned under the screw 134, the master switch 183 will be closed to place the apparatus in readiness for operation. When the first mold is moved into stripping position, the projection 131 opposite such mold will engage 150

and operate the switch X, closing the latter. A circuit will then be completed through the conductor 172, the conductor 179, the switch X, the contactor switch 180, the conductor 182, the 5 switch 183, the limit switches I and VI, the coil of the contactor switch 175, the coil of the contactor switch 178, and the coil of the contactor switch 174. The contactor switches 175, 178, and 174 thereby will be closed, and the motor will 10 drive the screw downwardly toward the mold. When the head 43 engages the mold in a manner to operate the rod 50, the latter will move the switch I to open position, thus breaking a circuit through the coils of the contact switches 175, 178, and 174 so as to stop the motor. If, 15 through inadvertence, the motor 32 should be caused to drive the screw downwardly when no mold is in stripping position, the limit switch VI will be opened upon engagement of the bracket 20 53 with the switch arm so as to break the circuit and prevent over travel of the screw.

That part of the circuit which controls the operation of the motor for moving the screw upwardly will now be described. A conductor 25 184 leads from the conductor 179 through a master switch 185, the limit switch V carried by the tower, the coils of the contactor switches 176, 177, and 174, and thence to the side 150 of the supply line. In operation, if it is desired 30 to move the screw upwardly under manual control, the master switch 185 is closed so as to effect closing of the contactor switches 176, 177, and 174, whereby the motor will operate in the reverse direction to move the screw upwardly.

35 In accordance with the invention, means are provided for starting the screw on its upward travel as soon as the stripping operation has been completed. In the circuit shown, a contactor switch 186 is connected directly across 40 the manually operable switch 185, and means are provided for closing the contactor switch automatically upon the completion of the stripping operation. To this end a conductor 187 leads from the conductor 172 through the coil 45 of the contactor switch 186, the coil of a contactor switch 188, the plunger operated limit switch VIIa and the limit switch IV to the side 150 of the line. A conductor 189 is interposed between one side of the contactor switch 188 50 and the limit switch IV, so that, when the contactor switch 188 is once closed through the closing of the switch VIIa, the circuit will be made across the points of the contactor 188, maintaining the coil of the latter energized so 55 as to seal the circuit closed even after the switch VIIa is opened.

In operation, assuming that the screw is in its lower position with the head 43 in engagement with the mold, the switches 186, 188, VIIa, 60 and IV will be in the positions shown in Figure 17, and the circuit through the coils of the contactor switches 176, 177, and 174 will be open. When the plunger 59 reaches the upper limit of its travel, it will engage and close automatically the switch VIIa. This will close a circuit through the conductors 172 and 187, the contactor switch 186, the closed switch VIIa, and the switch VII. Energizing of the coil of the contactor switch 186 will close this switch so 65 as to complete a circuit around the master switch 185 so that the coils of the contactor switches 176, 177, and 174 will be closed in the manner previously described, thereby starting the motor in the reverse direction so as to move the screw 70 upwardly. It will be understood that the switch 75 VIIa will be held closed for a short time only, that is, only during the time when the plunger 59 is in its extreme upper position. However, as previously stated, once the coil of the contactor switch 188 has been energized, this contactor in closing seals its own circuit, so that, even after the switch VIIa is opened and the plunger moved downwardly, the motor will continue to drive the screw upwardly. When the screw reaches the desired upper limit of its travel, the limit switch IV will be operated in the manner previously described so as to break the circuit through the coils of the contactors 176, 177, and 174 and to bring the screw to rest. If it is desired to move the screw still further upwardly in order to permit the passage of a locomotive under the tower, the switch 185 may be closed. As previously stated, this will close the contactors 176, 177, and 174 so as to operate the motor in the reverse direction to move the screw upwardly. When the screw approaches the extreme limit of its upward travel, the switch V will be operated as previously described so as to break the circuit through the coils of the contactors referred to, causing the contactors to open and stopping the motor.

The control circuit for the motor mechanism 92 which operates the valve 84 is shown in Figure 18. A conductor 190 connects one side of the motor 92 to the side 150 of the main line, and a conductor 191 connects the other side of the motor to the side 150 of the main line. Normally open, contactor switches 192, 193 are interposed respectively in the conductors 190 and 191.

A conductor 194 leads through the coils of the contactors 192 and 193 and through the coil of the contactor 180 of the screw motor control circuit shown in Figure 17, and then through the plunger operated limit switch VII and the limit switch III, carried by the top of the screw 34 to the conductor 191, being connected to the latter between the contactor 193 and the motor 92.

A conductor 195 is connected across the contactor 193, and a manually operable push button 196 is interposed in the conductor 195.

In operation, assuming that the head 43 has not yet moved into engagement with the mold, the various switches will be in the positions shown in Figure 18. When the head engages the mold so as to move the rod 50 upwardly, the switch III will be closed in the manner described previously. This will "set up" the valve control circuit, placing it in readiness for effecting the start of operation of the motor 92 under manual control of the push button 196. At this time, before the push button is closed, there will be no circuit closed through the coils of the contactors 192 and 193, and consequently these switches will remain open. When the operator closes the push button 196, a circuit will be closed through the conductor 194, the coils of the contactors 192 and 193, the coil of the contactor 180 (Figure 17), the limit switch VII, the limit switch III, the push button 196 and the conductors 195 and 191. This will energize the coils of the contactors 192 and 193 so as to close these switches to start the motor 92. After the motor has been started, the push button is opened, but due to the prior closing of the contactors 192 and 193, the coils thereof will be connected across the line in parallel with the motor 92 so as to remain energized and to maintain the contactors closed. The motor 92 thereby will continue to operate so as to move the valve 84 to its upper position wherein fluid under pressure will be delivered to the cylinder 56, and the 150

plunger 59 will be moved upwardly to perform a stripping operation. When the stripping operation has been completed, the projection 64, carried by the plunger 59, will open the limit switch VII, as previously described, thereby breaking the circuit through the conductor 194 and consequently deenergizing the coils of the contactors 192 and 193 so as to permit the latter to open, whereby the motor 92 will be stopped and the springs 90 will return the valve stem 85 to its lower position so that the cylinder 56 will be connected to the tank T and the plunger 59 will return to its lower position.

It will be noted that when the coils of the contactors 192 and 193 are energized so as to effect operation of the motor 92 and upward movement of the plunger 56, the coil of the contactor 180 likewise will be energized, so that the switch 180 will be opened, and it will be impossible to start operation of the screw motor 32 while the plunger is moving upwardly.

When the limit switch VII is opened and the plunger begins to move downwardly, the coil of the contactors 180 will be deenergized, thereby allowing the contactors 180 to close and set up the control circuit for the screw motor 32. Simultaneously with the opening of the switch VII, the switch VIIa will be closed so as to start the screw motor 32 in a direction to move the screw 34 upwardly in the manner stated in describing the circuit shown in Figure 17.

Figure 19 shows the control circuit for the motor mechanism 82 which operates the valve 74 to shift the flow of fluid from the cylinder 56 to the cylinder 56'. A conductor 197 is interposed between one side of the motor 82 and the side 150 of the main line, and a conductor 198 is interposed between one side of the motor 82 and the side 151 of the main line. A manually operable switch 199 is interposed in the conductor 198. When the switch 199 is opened so that the motor 82 is not operating, the springs 80 of the valve mechanism 74 will maintain the valve stem in its lower position so that fluid will be directed to the cylinder 56. When the switch 199 is closed so as to start the motor 82, the valve stem 75 will be moved to its upper position and fluid will be directed to the cylinder 56'.

It will be understood that circuits similar to those shown in Figures 17 and 18 are provided for controlling the operation of the screw 34' and the valve 84'. The circuit shown in Figure 16 for controlling the rack motor is the only circuit needed for this purpose, inasmuch as the molds on one side of the car are located directly opposite the molds on the other side of the car so that the molds are spotted under the tower in pairs.

The various elements of the electrical control circuits have been shown diagrammatically only, it being understood that the switches, contactors, push buttons and the like are all of standard construction and that the details thereof are not relevant to the invention. The usual safety devices such as overload and low voltage circuit breakers may be included in the circuits but have been omitted from the disclosure in the interest of simplicity since they are not essential to an operative arrangement.

It is apparent that apparatus constructed and arranged in accordance with my invention facilitate the stripping of ingots from big end up molds to such an extent as to render the production of high quality steel more economical than has been possible with stripping apparatus em-

ployed heretofore. Not only does the interlocked control of the mold positioning, holding, and stripping mechanisms provide for increased stripping speed and greater production from a given number of molds, but the control also prevents the accidental operation of any one of the mechanisms at such time as might result in injury to the machinery or operators.

From the foregoing it will be apparent that in accordance with the method of controlling the operation of the stripping apparatus I utilize return movement of the stripping device for effecting movement of the holding device to inoperative position, and utilize stripping movement of the stripping device for preventing movement of the mold support during the stripping operation and for preventing movement of the holding device during the stripping operation. Movement of the mold support is utilized for arresting movement thereof when a mold has reached stripping position as well as for controlling the operation of the stripping device. Movement of the holding device in turn is utilized for controlling operation of the stripping device and the mold support. In accordance with a further feature of the invention, the method of stripping ingots consists in holding the mold stationary, applying stripping pressure to the ingot, and, in case the ingot has a tendency to stick in the mold, automatically applying increased pressure to the ingot to assure stripping thereof.

Although the apparatus disclosed herein embodies the invention in a practical and in the at present preferred form, it will be understood that various modifications may be made without departing from the spirit of the invention as defined in the claims.

I claim:

1. The combination with an ingot stripping apparatus; of a mold support mounted for movements with respect to the apparatus for positioning a mold in stripping position relative to said apparatus and mechanism for moving said support comprising a member mounted for movements in the direction of travel of the mold support, means fixed with respect to said stripping apparatus and having driving connection with said member for operating the latter, coupling means connected to and being movable with said member and also being movable relative to said member into and out of engagement with said support for effecting driving relation between said member and said support, and a control device operatively connected to said coupling means and being operable to move said coupling means into or out of engagement with said mold support.

2. The combination with an ingot stripping apparatus; of a mold support mounted for movements with respect to said apparatus for positioning a mold in stripping position relative to said apparatus and mechanism for moving said support comprising; a bar mounted for reciprocatory movement of limited extent in the direction of travel of said support, a motor fixed with respect to said stripping apparatus and being operatively connected to said bar for reciprocating the latter, and a driving connection mounted on said bar for movements therewith and being movable relative to said bar into and out of engagement with said support.

3. The combination with an ingot stripping apparatus; of a mold support mounted for movements with respect to said apparatus for positioning a mold in stripping position relative to said apparatus; a bar mounted for longitudinal move-

- ment in the direction of travel of said support; means operatively connected to said bar for reciprocating the latter; a pawl pivotally mounted on said bar and having its nose movable into engagement with said support for effecting driving connection between said bar and said support; and control means operatively connected to said pawl for moving the latter into and out of engagement with said support.
- 10 4. The combination with an ingot stripping apparatus; of a mold support mounted for movements with respect to said apparatus for positioning a mold in stripping position relative to said apparatus; a bar mounted for longitudinal movement in the direction of travel of said support; means operatively connected to said bar for reciprocating the latter; a pawl pivotally mounted on said bar and having its nose movable into engagement with said support; means operatively connected to said pawl for urging the latter into operative position with its nose engaging said support; a control device; and means providing operative connection between said device and said pawl irrespective of the position of said bar for moving the pawl to disengage its nose from said support.
5. The combination with an ingot stripping apparatus; of a mold support mounted for movements with respect to said apparatus for positioning a mold in stripping position relative to said apparatus; a bar mounted for longitudinal movement in the direction of travel of said support; means operatively connected to said bar for reciprocating the latter; a pawl pivotally mounted on said bar and having its nose movable into engagement with said support; means operatively connected to said pawl for urging the latter into operative position with its nose engaging said support; a control device; means providing operative connection between said device and said pawl irrespective of the position of said bar for moving the pawl to disengage its nose from said support; and means on said bar for locking said pawl in operative position.
- 45 6. The combination with an ingot stripping apparatus; of a mold support mounted for movements with respect to said apparatus for positioning a mold in stripping position relative to said apparatus; a bar mounted for longitudinal movement in the direction of travel of said support; means operatively connected to said bar for reciprocating the latter; a pawl pivotally mounted on said bar and having its nose movable into engagement with said support; means operatively connected to said pawl for urging the latter into operative position with its nose engaging said support; a rail extending parallel and adjacent to said bar; and means mounting said rail for movements with respect to the bar and into engagement with said pawl for moving the latter to inoperative position.
7. The combination with an ingot stripping apparatus; of a mold support mounted for movements with respect to said apparatus for positioning a mold in stripping position relative to said apparatus; a bar mounted for longitudinal movement in the direction of travel of said support; means operatively connected to said bar for reciprocating the latter; a pawl pivotally mounted on said bar and having its nose movable into engagement with said support; means operatively connected to said pawl for urging the latter into operative position with its nose engaging said support; a rail extending parallel and adjacent to said bar; a pair of spaced parallel levers pivotally connected to said rail; and means for rocking one of said levers to move said rail into engagement with said pawl.
8. The combination with an ingot stripping apparatus; of a mold support mounted for movements with respect to said apparatus for positioning a mold in stripping position relative to said apparatus; a bar mounted for longitudinal movement in the direction of travel of said support; means operatively connected to said bar for reciprocating the latter; a pawl pivotally mounted on said bar and having its nose movable into engagement with said support; means operatively connected to said pawl for urging the latter into operative position with its nose engaging said support; a latch pivotally connected to said bar and being movable into engagement with said pawl for locking the latter in operative position; a rail extending parallel and adjacent to said bar; and means mounting said rail for movements with respect to the bar and into engagement with said pawl and said latch for moving both to inoperative positions.
9. The combination with an ingot stripping apparatus; of a mold supporting car mounted for movements with respect to said apparatus for positioning a mold in stripping position relative to said apparatus; a rack bar mounted for longitudinal movements in the direction of travel of said car; a motor having driving connection with said rack bar for operating the latter in both directions; and means mounted on said rack bar for movements with the latter and also being movable relative thereto into engagement with said car for effecting driving connection between said rack bar and said car and being also movable out of engagement with said car.
10. The combination with an ingot stripping apparatus; of a mold supporting car mounted for movements with respect to said apparatus for positioning a mold in stripping position relative to said apparatus; a rack bar mounted for longitudinal movements in the direction of travel of said car; a motor having driving connection with said rack bar for operating the latter in both directions; a pawl pivotally mounted on said rack bar and having its nose movable with the latter and also being movable relative thereto into and out of engagement with said car; means operatively connected to said pawl for urging the latter into operative position with its nose in engagement with said car; a rail extending parallel and adjacent to said rack bar; and means mounting said rail for movements with respect to said rack bar and into engagement with said pawl irrespective of the position of the rack bar for moving the pawl to inoperative position.
11. The combination with an ingot stripping apparatus; of a mold supporting car mounted for movements with respect to said apparatus for positioning a mold in stripping position relative to said apparatus; a rack bar mounted for longitudinal movements in the direction of travel of said car; a motor having driving connection with said rack bar for operating the latter in both directions; a pawl pivotally mounted on said rack bar and having its nose movable with the latter and also being movable relative thereto into and out of engagement with said car; means operatively connected to said pawl for urging the latter into operative position with its nose in engagement with said car; a latch pivotally connected to said rack bar and being movable into engagement with said pawl for locking the latter in operative position; a rail extending parallel to

- said bar; and means mounting said rail for movements into engagement with said pawl and said latch irrespective of the position of the rack bar for moving said pawl and latch to inoperative 5 positions.
12. The combination with an ingot stripping apparatus; of a mold support mounted for movements with respect to the apparatus for positioning a mold in stripping position relative to said 10 apparatus; driving means for moving said mold support to place a supported mold in stripping position; and control means responsive to movement of said mold support for automatically arresting movement of said mold support when said 15 supported mold has been moved to stripping position.
13. The combination with an ingot stripping apparatus; of a mold support mounted for movements with respect to the apparatus for positioning a mold in stripping position relative to said 20 apparatus; a stationary motor; means for transmitting drive from said motor to said mold support for moving the latter to place a supported mold in stripping position; and control 25 means for said motor operable automatically by engagement by said support when said supported mold has reached stripping position for arresting operation of said motor.
14. The combination with an ingot stripping apparatus; of a mold support mounted for movements with respect to the apparatus for positioning a mold in stripping position relative to said 30 apparatus; an electric motor; means for transmitting drive from said motor to said mold support for moving the latter to place a supported mold in stripping position; a motor stopping limit switch in circuit with said motor; and means operable when said supported mold has reached stripping position for automatically operating said limit switch to stop operation of 35 the motor.
15. The combination with an ingot stripping apparatus; of a mold support mounted for movements with respect to the apparatus for positioning a mold in stripping position relative to said 40 apparatus; an electric motor; means for transmitting drive from said motor to said mold support for moving the latter to place a supported mold in stripping position; a motor stopping limit switch for controlling operation of said 45 motor; and means connected to said switch and being engageable by said support when said supported mold has reached stripping position for operating said switch to arrest operation of the motor.
16. The combination with an ingot stripping apparatus; of a mold support mounted for movements with respect to said apparatus for positioning successively a plurality of molds carried 50 by the support in stripping position relative to said apparatus; an electric motor having driving connection with said mold support for moving the latter; a motor stopping limit switch for controlling operation of said motor; means connected to said switch and being engageable by said support when a mold has reached stripping position for operating said switch to arrest operation of the motor; and a second switch for controlling operation of said motor independently of said limit switch.
17. The combination with an ingot stripping apparatus; of a mold support mounted for movements with respect to said apparatus for positioning successively a plurality of molds carried 55 by the support in stripping position relative to said apparatus; an electric motor having driving connection with said mold support for moving the latter; a motor stopping limit switch for controlling operation of said motor; means connected to said switch and being engageable by said support when a mold has reached stripping position for operating said switch to arrest operation of the motor; and a second switch for controlling operation of said motor independently of said limit switch.
18. The combination with an ingot stripping apparatus; of a mold support mounted for movements with respect to said apparatus for positioning successively a plurality of molds carried by the support in stripping position relative to said apparatus; a rack bar connected to said support for moving the latter; an electric motor having driving connection with said rack bar for operating the latter; a motor stopping limit switch for controlling operation of said motor; means connected to said switch and being engageable by said support when a mold has reached stripping position for operating said switch to arrest operation of the motor; and a second switch for controlling operation of said motor independently of said limit switch.
19. The combination with an ingot stripping apparatus; of a mold support mounted for movements with respect to said apparatus for positioning successively a plurality of molds carried by the support in stripping position relative to said apparatus; a rack bar connected to said support for moving the latter; an electric motor having driving connection with said rack bar for operating the latter; a motor stopping limit switch for controlling operation of said motor; means connected to said switch and being engageable by said support when a mold has reached stripping position for operating said switch to arrest operation of the motor; and other motor stopping limit switch means in circuit with said motor and being engageable by said rack when the latter approaches the end of its travel for stopping said motor to prevent over travel of said rack bar.
20. The combination with an ingot stripping apparatus; of a mold support mounted for movements with respect to said apparatus for positioning successively a plurality of molds carried by the support in stripping position relative to said apparatus; an electric motor having driving connection with said mold support for moving the latter; a motor stopping limit switch for controlling operation of said motor; a plurality of projections on said support, one opposite each mold supported thereby; means connected to said switch and being engageable by said projections individually when the associated molds have reached stripping position for operating said switch to arrest operation of the motor; and a second switch for controlling operation of said motor independently of said limit switch.
21. A device for holding ingot molds against movement during stripping of ingots therefrom comprising a head including a body member; a pair of spaced substantially parallel mold-engaging legs mounted on said body for movements towards and from each other; and means operatively connecting said legs and being operable to vary the distance between the legs to adapt the latter for engagement with molds of different sizes.
22. A device for holding ingot molds against movement during stripping of ingots therefrom comprising a head including a body member; a pair of spaced substantially parallel mold-engaging

- ing legs slidably mounted on said body for movements towards and from each other; and a captive screw mounted on said body for rotary movements and having threaded connection with said legs. 23. In apparatus for stripping an ingot from an ingot mold, the combination of a mold support; a holding device mounted for movement into engagement with a mold in stripping position on said support; means operatively connected to said holding device for driving the latter into mold-engaging position; and control means operatively connected with said driving means and being responsive to engagement of said hold down device with said mold for automatically stopping operation of said driving means. 24. In apparatus for stripping an ingot from an ingot mold, the combination of a mold support; a holding device mounted for movement into engagement with a mold in stripping position on said support; a motor having driving connection with said holding device for moving the latter into mold-engaging position; and control means operatively connected with said motor and being carried by said holding device and being responsive to engagement of said holding device with said mold for automatically stopping operation of said motor. 25. In apparatus for stripping an ingot from an ingot mold, the combination of a mold support; a screw mounted for movements parallel to the axis of a mold in stripping position on said support; a head on said screw engageable with said mold; a captive nut having threaded engagement with said screw for operating the latter; an electric motor having driving connection with said nut; and means including a motor stopping switch in circuit with said motor, said means being responsive to engagement of said head with said mold for stopping said motor. 26. In apparatus for stripping an ingot from an ingot mold, the combination of a mold support; a screw mounted for movements parallel to the axis of a mold in stripping position on said support; a mold-engaging head mounted on said screw and having lost motion connection therewith; a captive nut having threaded connection with said screw for operating the latter; an electric motor having driving connection with said nut; a motor stopping switch in circuit with said motor and being mounted on said screw; and a connection between said head and said switch for operating the latter to stop said motor when said head engages the mold on said support and relative movement of said head and screw is produced. 27. In apparatus for stripping an ingot from an ingot mold, the combination of a mold support; a driven member mounted for movements towards and from said support; a mold-engaging head loosely mounted on said driven member for limited movement relative to said member in the direction of travel of the latter; an electric motor having driving connection with said driven member for operating the latter; a motor stopping switch carried by said driven member and in circuit with said motor for controlling operation thereof; and a rod carried by said member extending longitudinally thereof and having one of its ends in engagement with said mold-engaging head and its other end disposed for engagement with said switch for operating the latter to stop said motor when said head engages a mold in stripping position on said support. 28. In apparatus for stripping an ingot from an ingot mold, the combination of a mold support; a screw mounted for vertical movements above said support; a mold-engaging head mounted on the lower end of said screw for limited movements relative to the screw in the line of travel of the latter; an electric motor having driving connection with said screw; a stop switch mounted on the upper end of said screw and being connected in circuit with said motor; and a rod extending longitudinally through said screw, the lower end of the rod being in engagement with said head and the upper end of the rod being adapted to engage and operate said stop switch when the head engages a mold on said support. 29. In apparatus for stripping an ingot from an ingot mold, the combination of a mold support; a holding device mounted for movement into engagement with a mold in stripping position on said support; means operatively connected to said holding device for driving the latter into mold-engaging position; control means operatively connected with said driving means and being responsive to engagement of said holding device with said mold for automatically stopping operation of said driving means; and other control means independent of said first named control means for limiting the total travel of said holding device. 30. In apparatus for stripping an ingot from an ingot mold, the combination of a mold support; a screw mounted for vertical movements above said support; a mold-engaging head mounted on the lower end of said screw for limited movements relative to the screw in the line of travel of the latter; an electric motor having driving connection with said screw; a stop switch mounted on the upper end of said screw and being connected in circuit with said motor; a rod extending longitudinally through said screw, the lower end of the rod being in engagement with said head and the upper end of the rod being adapted to engage and operate said stop switch when the head engages a mold on said support; and limit switch means in circuit with said motor and operable by said screw when the latter approaches the limit of its travel for preventing over travel thereof. 31. In apparatus for stripping an ingot from an ingot mold, the combination of a mold support; a screw mounted for vertical movements above said support; a mold-engaging head mounted on the lower end of said screw for limited movements relative to the screw in the line of travel of the latter; an electric motor having driving connection with said screw; means including a stop switch mounted on the upper end of said screw and being connected in circuit with said motor for effecting operation of said motor in a direction to drive said screw downwardly; a rod extending longitudinally through said screw, the lower end of the rod being in engagement with said head and the upper end of the rod being adapted to engage and operate said stop switch when the head engages a mold on said support; and means including a switch for closing a circuit through said motor for effecting operation of said motor in the opposite direction to drive said screw upwardly independently of said stop switch. 32. In apparatus for stripping an ingot from an ingot mold, the combination of a mold support; a screw mounted for vertical movements above said support; a mold-engaging head mounted on the lower end of said screw for limited movements relative to the screw in the line of travel of the latter; an electric motor having

- driving connection with said screw; a stop switch mounted on the upper end of said screw in circuit with said motor; a rod extending longitudinally through said screw, the lower end of the rod 5 being in engagement with said head and the upper end of the rod being adapted to engage and operate said stop switch when the head engages a mold on said support; limit switch means in circuit with said motor and operable by said screw 10 when the latter approaches the limit of its travel for preventing over travel thereof; and other switch means for closing a circuit through said motor independently of said stop switch and said limit switch means.
- 15 33. In apparatus for stripping an ingot from an ingot mold, the combination of a mold support; means for holding a mold on said support; an ingot stripping device associated with said holding means; power operated means engageable 20 with said stripping device for operating the latter; means for supplying power to said power operated means; and control means responsive to resistance due to sticking of the ingot in the mold for automatically supplying increased power 25 to overcome such sticking resistance.
34. In apparatus for stripping an ingot from an ingot mold, the combination of a mold support; means for holding a mold on said support; an ingot stripping device associated with said holding means; a hydraulically actuated plunger engageable with said stripping device for operating the latter; means for supplying fluid under pressure to said plunger; and means responsive to resistance due to sticking of the ingot on the mold for automatically supplying fluid to said 30 plunger under increased pressure to overcome such sticking resistance.
35. In apparatus for stripping an ingot from an ingot mold, the combination of a mold support; means for holding a mold on said support; an ingot stripping device associated with said holding means; a hydraulic plunger engageable with said stripping device for operating the latter; a pump having a predetermined maximum 40 discharge pressure; a pipe line for delivering fluid under pressure from said pump to said plunger; a second pump having a predetermined maximum discharge pressure higher than that of said first pump; a pipe line for delivering fluid under pressure from said second pump to 45 said plunger; a check valve in said first pipe line arranged to permit flow therethrough in a direction away from said first pump but not in the opposite direction; and means operatively connected to said pumps for driving the latter.
36. In apparatus for stripping an ingot from an ingot mold, the combination of a mold support; means for holding a mold on said support; an ingot stripping device associated with said holding means; a hydraulic plunger engageable with said stripping device for operating the latter; a low pressure pump having a high rate of discharge; a pipe line for delivering fluid under pressure from said pump to said plunger; a high 50 pressure pump having a low rate of discharge; a pipe line for delivering fluid under pressure from said second pump to said plunger; a check valve in said first pipe line arranged to permit flow therethrough in a direction away from said 55 first pump but not in the opposite direction; and means operatively connected to said pumps for operating the latter.
37. In apparatus for stripping an ingot from an ingot mold, the combination of a mold support; means for holding a mold on said support; 60 an ingot stripping device associated with said holding means; a cylinder; a hydraulic plunger therein engageable with said stripping device for operating the latter; a pump; a pipe line for supplying fluid under pressure from said pump to said cylinder; a fluid exhaust; electrically actuated valve means connected in said pipe line for placing said cylinder in communication with said pump or said exhaust; and means including a switch in circuit with said electrically actuated valve means, said means being responsive to movement of said plunger during a stripping operation for effecting operation of said valve means to place said cylinder in communication with said exhaust. 80
38. In apparatus for stripping an ingot from an ingot mold, the combination of a mold support; means for holding a mold down on said support; a vertically movable stripper rod associated with said support and holding means; a hydraulic cylinder mounted underneath and substantially coaxial with said stripper rod; a hydraulic plunger therein engageable with said stripper rod for operating the latter; means for supplying fluid under pressure to said cylinder; electrically actuated means for controlling the supply of fluid to said cylinder; a switch in circuit with said means and mounted in fixed relation to said cylinder; and an apron connected to said plunger and being engageable with said switch 95 for operating the latter during a stripping operation to effect actuation of said control means and stopping of supply of fluid to said cylinder. 100
39. In apparatus for stripping ingots from ingot molds, the combination of a movable mold support; a mold holding device mounted for movements into mold-engaging position; driving means for operating said mold support to position a supported mold in stripping position relative to said apparatus; and control means associated with said driving means and being responsive to engagement of the mold holding device with said mold for preventing operation of said driving means. 110
40. In apparatus for stripping ingots from ingot molds, the combination of a movable mold support; a mold holding device mounted for movements into mold-engaging position; an electric motor having driving connection with said mold support for moving the latter to position a supported mold in stripping position relative to said apparatus; a switch in circuit with said motor; and means operatively connected to said switch and being responsive to engagement of said holding device with said mold for operating 115 said switch to prevent operation of said motor. 120
41. In apparatus for stripping ingots from ingot molds, the combination of a movable mold support; a mold holding device mounted for movements into mold-engaging position; driving means for operating said mold support to position a supported mold in stripping position relative to said apparatus; driving means operatively connected to said holding device for operating the latter into mold-engaging position; and control 125 means operatively connected to said driving means and being responsive to engagement of the mold holding device with the mold for preventing operation of both of said driving means. 130
42. In apparatus for stripping ingots from ingot molds, the combination of a reciprocable stripper plunger; a movable mold support; driving means operatively connected with said support for moving the latter to position a supported mold adjacent said plunger in stripping position; 140

- means operatively connected to said plunger for operating the latter; and control means associated with said support driving means and being operable by said plunger when the latter begins a stripping operation for preventing operation of said support driving means during the stripping operation. 43. In apparatus for stripping ingots from ingot molds, the combination of a reciprocable stripper plunger; means connected to said plunger for operating the latter; a movable mold support; an electric motor having driving connection with said support for moving the latter to position a supported mold in stripping position relative to said plunger; a switch in circuit with said motor; means connected to said switch for urging it to open position to prevent operation of said motor; and means connected to said plunger and being engageable with said switch when the plunger is in retracted inoperative position for closing said switch to permit operation of said motor. 44. In apparatus for stripping ingots from ingot molds, the combination of a movable mold support; a mold holding device mounted for movements into mold-engaging position; means for operating said support to position a supported mold in stripping position relative to said holding device; driving means connected to said mold holding device for moving the latter into engagement with a mold; control means operatively connected to said driving means for controlling operation of the latter; and means connected to said control means and being engageable by said support when the latter has moved a mold to stripping position for operating said control means. 45. In apparatus for stripping ingots from ingot molds, the combination of a movable mold support; a mold holding device mounted for movements into mold-engaging position; means for operating said support to position a supported mold in stripping position relative to said holding device; an electric motor connected to said mold holding device for moving the latter into engagement with a mold; and means including a switch in circuit with said motor for controlling operation thereof said means being responsive to movement of said support for controlling operation of said support when the latter has moved a mold into stripping position. 46. In apparatus for stripping ingots from ingot molds, the combination of a movable mold support; a mold holding device mounted for movements into mold-engaging position; driving means connected to said support for moving the latter to position a mold in stripping position relative to said holding device; driving means connected to said mold holding device for moving the latter into engagement with a positioned mold; control means for controlling the operation of both driving means; and means for automatically operating said control means when said support has moved a mold to stripping position. 47. In apparatus for stripping ingots from ingot molds, the combination of a mold support; a holding device mounted for movements into mold-engaging position relative to a mold positioned on said support; driving means connected to said mold holding device for operating the latter; a reciprocable stripper plunger mounted for movements relative to said holding device; and control means operatively connected to said driving means and being responsive to movement of said plunger for controlling operation of said driving means at the end of a stripping operation of the plunger. 48. In apparatus for stripping ingots from ingot molds, the combination of a mold support; a holding device mounted for movements relative to a mold positioned on said support into mold-engaging position; an electric motor connected to said mold holding device for operating the latter towards and from a mold in stripping position; a reciprocable stripper plunger mounted for movements relative to said holding device; and means including a switch in circuit with said motor and being responsive to movement of said plunger when the latter completes a stripping operation for starting said motor to retract said holding device. 49. In apparatus for stripping ingots from ingot molds, the combination of a mold support; a holding device mounted for movements relative to a mold positioned on said support into mold-engaging position; an electric motor connected to said mold holding device for operating the latter towards and from a mold in stripping position; a reciprocable stripper plunger mounted for movements relative to said holding device; means including a switch in circuit with said motor and being responsive to engagement of said hold down device with a mold for automatically stopping operation of said motor; and means including a switch in circuit with said motor and being responsive to movement of said plunger when the latter completes a stripping operation for starting said motor to retract said holding device. 50. In apparatus for stripping ingots from ingot molds, the combination of a mold support; a holding device mounted for movements relative to a mold positioned on said support into mold-engaging position; a reciprocable stripper device mounted for movements relative to said holding device; means for supplying power to said stripping device; and means operatively connected with said power supplying means and being responsive to engagement of said holding device with a mold for controlling application of power to said stripping device. 51. In apparatus for stripping ingots from ingot molds, the combination of a mold support; a holding device mounted for movements relative to a mold positioned on said support into mold-engaging position; a hydraulically actuated stripper plunger mounted for reciprocation relative to said holding device; a pump for supplying fluid under pressure to said plunger; a hydraulic connection between said pump and plunger; a valve in said connection for controlling the supply of fluid to said plunger; and control means connected to said valve and being responsive to engagement of said holding device with a mold on said support in stripping position for opening said valve to said pump and plunger. 52. In apparatus for stripping ingots from ingot molds, the combination of a mold support; a holding device mounted for movements relative to a mold positioned on said support into mold-engaging position; a hydraulically actuated stripper plunger mounted for reciprocation relative to said holding device; a pump for supplying fluid under pressure to said plunger; a hydraulic connection between said pump and plunger; a valve in said connection for controlling the supply of fluid to said plunger; electrically actuated means connected to said valve for operating the latter; switch means in circuit with said elec-

trically actuated means; and means carried by said holding device and being responsive to engagement of the latter with a mold on said support in stripping position for operating said switch means.

53. In apparatus for stripping ingots from ingot molds, the combination of a mold support; a holding device mounted for movements relative to a mold positioned on said support into mold-engaging position; an electric motor connected to said holding device for operating the latter; a hydraulically actuated stripper plunger mounted for reciprocation relative to said holding device; a pump for supplying fluid under pressure to said plunger; a hydraulic connection between said pump and plunger; a valve in said connection for controlling the supply of fluid to said plunger; electrically actuated means con-

nected to said valve for operating the latter; switch means in circuit with said motor; switch means in circuit with said valve operating means; and means connected to both of said switch means and being responsive to engagement of said holding device with a mold for operating said switch means. 80

54. In apparatus for stripping ingots from ingot molds, the combination of a mold support; a hold-down member mounted for downward movement toward a mold, in stripping position on said support; a head loosely mounted on said hold-down member and being engageable with the top of said mold; a universal joint connection between said head and said member; and means 85 for operating said hold-down member. 90
